INVENTOR

UNITED STATES PATENT OFFICE

95,044

DESIGN FOR A MATERNITY DRESS ENSEMBLE

Irwin Kranz, New York, N. Y.

Application November 8, 1934, Serial No. 53,939

Term of patent 3½ years

To all whom it may concern:

Be it known that I, Irwin Kranz, a citizen of the United States of America, residing in Manhattan, county of New York, and State of New York, have invented the new, original, and ornamental Design for Maternity Dress Ensemble, of which the following is a specification, reference being had to the accompanying drawing, forming part thereof, wherein,

Fig. 2 is a rear view of the dress ensemble shown in Fig. 1, the front panel being provided with snap fasteners to permit of putting on of the garment, and the belt at the waist line in back being also so provided.

I claim:

The ornamental design for a maternity dress ensemble, substantially as shown and described.

IRWIN KRANZ.
